KNOCK-OFF BLOCK

William F. Lantz, Lefors, Tex.

Application July 23, 1937, Serial No. 155,300

3 Claims. (Cl. 74—593)

This invention relates to devices of the character commonly referred to in the oil field as a "pull-rod retainer" or "knock-off block" whereby the rod line may be connected with or disconnected from pumping power in a safe manner.

An object of the present invention is to provide a device of this character which will be substantially fool-proof and will have many advantages over the types of pull-rod retainers or knock-off blocks now generally resorted to.

The invention together with its objects and advantages will be best understood from a study of the following description taken in connection with the accompanying drawings wherein:

Figure 1 is a side elevational view illustrating the application of the invention and with the pull-rod retainer or knock-off block in a working position.

20 Figure 2 is a view similar to Figure 1 and showing the pull-rod retainer or knock-off block in a lowered position, or in a position of rest.

Figure 3 is a top plan view of the device.

25 Figure 4 is a horizontal sectional view taken substantially on the line 4—4 of Figure 2.

Figure 5 is an end elevational view of a barrel forming part of the knock-off block, and

30 Figure 6 is a transverse sectional view through the barrel taken substantially on the line 6—6 of Figure 1.

Referring to the drawings by reference numerals it will be seen that the numeral 5 designates a knock-off post having in the upper end thereof and at diametrically opposite sides of the 35 post, slots 6 to accommodate a conventional rod line 7. To the end that one end of the rod line may be readily connected to a power unit said end is equipped with a stirrup 9 swivelly connected thereto through the medium of a clamp 40 8, and adapted to engage a hook 11 leading from the power unit.

The improved pull-rod retainer or knock-off block assembly comprises a transversely curved attaching plate or bracket 12 secured to the 45 knock-off post 5 in a positive manner either by being welded, bolted, or otherwise secured to the post.

Further the retainer or knock-off block includes a substantially tubular member or barrel 50 13 formed integrally with or otherwise secured intermediate its opposite ends to a tubular stem 14.

Links 15 at one end are pivoted to the stem 14 at opposite sides of the stem through the medium of bolts 16, and at the opposite end thereof said

links 15 are pivoted through the medium of bolts 17 to lugs 18 formed integrally with and projecting from the bracket plate 12.

Below the lugs 18 plate 12 is provided with lugs 19 in which is journaled a threaded shaft 20 provided at one end with a handle or crank 21. Threaded on the shaft 20 is the head 22 of a substantially T-shaped member 23. A yoke or fork 24 straddles the lower end of the stem 14 and is pivoted to the stem at opposite sides of the stem 10 as at 25. The shank 26 of the yoke 15 has screw-threaded engagement with the stem of the member 23 and threaded on the stem 26 is a jam nut 27 for securing stem 26 and the stem of the member 23 at the desired position of relative adjustment.

The head 22 of member 23 is secured at the desired adjustment on the shaft 20 through the medium of a set screw 28. Thus it will be seen that member 23 will rotate with the shaft 22 20 causing the stem 14 and barrel 13 to move vertically upwardly and downwardly, links 15 serving to restrain the movement of barrel 13 to the extent that the same will be at all times substantially parallel to the rod line 7.

At one end thereof the barrel 13 which in the top side thereof is provided with a longitudinal slot 29 to accommodate the rod line 7, is provided with a flange 30 so shaped as to conformably engage the knock-off post 5 when the barrel 13 is 30 in raised position.

At the end thereof remote from the flange 30 there is welded or otherwise secured to the barrel 13 a suitably slotted re-inforcing plate 31. The upper portion of the plate 31 at opposite sides 35 of the slot in the plate taper and project upwardly beyond the periphery of the barrel 13 as at 32 to provide guides. It is obvious that if the rod line 7 has for any reason moved out of alignment with the slot 29 of the barrel 13, said 40 wings or guides 32 will guide the rod 7 into engagement therewith.

The operation of the device is thought to be obvious. While the well is pumping the retainer or knock-off block assembly is in the lowered 45 position shown in Figure 2. When the accumulated fluid has been pumped from the well and operation of the pump is discontinued the operator steps on the handle or pedal member 21 and when the pull-rod has been pulled back by 50 the power to the limit of its retractive movement he presses down on the handle or pedal member 21 to swing the shaft 20 about its axis, causing the barrel 13 to move upwardly and at the same time in a direction toward the knock-off post 5, 55

the rod line 7 being received in the barrel through the slot 29. Thus when the weight of the sucker rod tends to return the pull rod, or rod line 7 the flanged end 30 of the barrel is bearing against the knock-off post 5 and the plate equipped end 31 of the barrel is engaged by the clamp 8 thereby retarding return movement of the rod line 7 and retaining the sucker rod at the upward limit of its movement. The parts are then in the position shown in Figure 1, and with the barrel 13 thus positioned between the knock-off post 5 and the clamp 8, connection between the pull or line rod 7 and the power unit may be broken by disengaging the hook 11 from the stirrup 9, so that the jack end of the line rod remains inoperative until the connection is restored.

When the pump is to be again placed in operation, the attendant engages the hook 11 with the stirrup 9, so that when the power operates to 20 retract the rod 7 the retaining barrel 13 automatically swings downwardly and off of the line rod 7 due to the greater weight of the barrel in comparison to the handle or pedal 21, and the weight of the sucker rod is again permitted to 25 retract the pull rod for a pumping stroke.

It will thus be seen that while the retainer or knock-off block assembly must be manually positioned for retaining the rod line in retracted 30 position, shift of the knock-off barrel 13 to clear the rod 7 is automatic upon resumption of the pumping operation and with the first pull stroke of the rod.

Having thus described the invention what is 35 claimed as new is:—

1. A knock-off block assembly for well-pumping and operating equipment, and comprising a knock-off post provided to accommodate a rod line, a supporting bracket secured to said post below the rod line, a retaining barrel adapted to be manually swung longitudinally and upwardly to a horizontal position to receive the rod line with one end of the barrel engaging said post and a relatively opposite end of the barrel engaging a protuberance on the rod line to hold the latter against reciprocation, said barrel having a stem depending therefrom intermediate the ends of the barrel, links pivotally connected at one end to said stem and at a relatively opposite end to said bracket, a lever-equipped shaft journaled on said bracket below the pivotal connection between the links and the bracket, and an adjustable arm connection between said shaft and said stem for transmitting movement of the shaft to said barrel to raise the latter into engagement with the rod line.

2. A knock-off block assembly for well-pumping and operating equipment, and comprising a knock-off post provided to accommodate a rod

line, a supporting bracket secured to said post below the rod line, a retaining barrel adapted to be manually swung longitudinally and upwardly to a horizontal position to receive the rod line with one end of the barrel engaging said post and a relatively opposite end of the barrel engaging a protuberance on the rod line to hold the latter against reciprocation, said barrel having a stem depending therefrom intermediate the ends of the barrel, links pivotally connected at one end to said stem and at a relatively opposite end to said bracket, a lever-equipped shaft journaled on said bracket below the pivotal connection between the links and the bracket, and an adjustable arm connection between said shaft and said stem for transmitting movement of the shaft to said barrel to raise the latter into engagement with the rod line, said adjustable arm connection including a substantial T-shaped member having a head portion secured to said shaft and a threaded stem portion, and a yoke having arms straddling said stem and pivoted to the latter at opposite sides of the stem together with a threaded shank screw-threadedly engaged with the stem of said T-shaped member.

3. A knock-off block assembly for well-pumping and operating equipment, and comprising a knock-off post provided to accommodate a rod line, a supporting bracket secured to said post below the rod line, a retaining barrel adapted to be manually swung longitudinally and upwardly to a horizontal position to receive the rod line with one end of the barrel engaging said post and a relatively opposite end of the barrel engaging a protuberance on the rod line to hold the latter against reciprocation, said barrel having a stem depending therefrom intermediate the ends of the barrel, links pivotally connected at one end to said stem and at a relatively opposite end to said bracket, a lever-equipped shaft journaled on said bracket, and an adjustable arm connection between said shaft and said stem for transmitting movement of the shaft to said barrel to raise the latter into engagement with the rod line, said adjustable arm connection including a substantial T-shaped member having a head portion secured to said shaft and a threaded stem portion, and a yoke having arms straddling said stem and pivoted to the latter at opposite sides of the stem together with a threaded shank screw-threadedly engaged with the stem of said T-shaped member, and said barrel at the rod line engaging end thereof having upstanding projections at opposite sides of the slot of the barrel for engaging the rod line for 40 guiding the barrel into engagement with said line.

WILLIAM F. LANTZ.
